(57) **CLAIM**

The ornamental design for a cooking stove for camping as shown and described.

DESCRIPTION

1. Cooking stove for camping

Figure 1.1 is a left perspective view of a cooking stove for camping in an unpacked state;

Figure 1.2 is a top plan view of the cooking stove for camping in a packed state;

Figure 1.3 is a left side elevational view of Figure 1.2;

Figure 1.4 is a right side elevational view of Figure 1.2;

Figure 1.5 is a front elevational view of Figure 1.1;

Figure 1.6 is a top plan view of Figure 1.1;

Figure 1.7 is a bottom plan view of Figure 1.1;

Figure 1.8 is a left elevational view of Figure 1.1;

Figure 1.9 is a right elevational view of Figure 1.1;

Figure 1.10 is a left perspective view of Figure 1.2;

Figure 1.11 is a front elevational view of Figure 1.2; and,

Figure 1.12 is a bottom plan view of Figure 1.2.

The broken lines in the drawings depict portions of the cooking stove for camping that form no part of the claimed design.

Cooking stoves for camping suitable for storage in vehicles; reproductions 1.2 to 1.4 and 1.10 to 1.12 show the claimed design in a storage state, whereas reproductions 1.1, 1.5 to 1.9 show the claimed design in a deployed state.

1 Claim, 12 Drawing Sheets
